UNITED STATES PATENT OFFICE.

CHARLES R. KEIL, OF TIFFIN, OHIO, ASSIGNOR TO UNITED STATES GLASS COMPANY,
OF PITTSBURGH, PENNSYLVANIA, A CORPORATION OF PENNSYLVANIA.

DESIGN FOR A GOBLET OR SIMILAR ARTICLE.

Application filed July 17, 1928. Serial No. 27,508. Term of patent 14 years.

To all whom it may concern:

Be it known that I, CHARLES R. KEIL, a citizen of the United States, residing at Tiffin, in the county of Seneca and State of Ohio, have invented a new, original, and ornamental Design for Goblet or Similar Article, of which the following is a specification, reference being had to the accompanying drawing, forming part thereof.

The figure is a perspective view of a tumbler or goblet, showing my new design.

I claim:

The ornamental design for a goblet or similar article, as shown.

CHARLES R. KEIL.
